UNITED STATES PATENT OFFICE.

HENRY H. JULICH, OF MOUNT HOPE, WISCONSIN.

PLOW.

939,704.

Specification of Letters Patent.

Patented Nov. 9, 1909.

Application filed March 8, 1909. Serial No. 482,111.

To all whom it may concern:

Be it known that I, HENRY H. JULICH, a citizen of the United States, and a resident of Mount Hope, in the county of Grant and State of Wisconsin, have invented a new and Improved Plow, of which the following is a full, clear, and exact description.

This invention relates to improvements in plows.

Among the principal objects of my invention is to provide a share which may be readily and quickly detached from the plow, and as readily and quickly replaced, thereby permitting the operator to separate the part of the implement which requires sharpening, and to carry the same to the forge or blacksmith shop.

Reference is to be had to the accompanying drawings forming a part of this specification, in which similar characters of reference indicate corresponding parts in all the views.

Figure 1 is a perspective view of a plow constructed in accordance with my invention; Fig. 2 is an isometric perspective of the plow, the land side being tilted up to give a view of the back of the moldboard; Fig. 3 is a detail view in isometric perspective of the moldboard and plate for attaching the share; Fig. 4 is a side view from the back of the share; Fig. 5 is a sectional view taken on the line 5—5 in Fig. 2; Fig. 6 is a sectional view of the share taken on the line 6—6 in Fig. 4; and Fig. 7 is a sectional view of the share taken on the line 7—7 in Fig. 4.

In the drawings, A indicates the moldboard of the plow, and is of the usual construction. To the back of the moldboard is secured either by riveting or by welding, a plate B which is of the same form as that part of the moldboard to which it is secured. In some instances I may dispense with the plate B and give to the moldboard an offset which will extend down behind the share, as does the plate B in the present instance. The moldboard in the present instance is securely braced to the landside C by means of the brace D. The landside is offset at the forward end, as shown at C' in Figs. 2 and 3, to receive the land side E' of the share E. In the forward end C' of the land side C is formed a slot F. The moldboard and land side C are secured to the handles G and plow beam H as in the usual construction.

The invention primarily consists in providing in the lower edge of the plate B a series of angular slots I, opening upward from the lower edge of the plate and having lateral and rearward extensions, as shown, and in providing the slot F in the forward end C' of the land side C. The share E is of the usual form, but is provided with headed extensions K, and at its point E' at the land side of said point, with a headed extension K', said extensions being adapted respectively to extend into the slots I and F. The extension K is mounted to turn in the point E', that when said extension reaches the inner extremity of the slot F, said extension may be turned across said slot, and thus fasten the landside C to the share E. The plate B is further provided with a flat spring detent or latch L, which is pivotally mounted at M and has a hand hold N. The detent has a lip O formed by bending the spring upon itself, and the lip O is of such width that when the extensions K are seated within the lateral extensions of the slots I and at the rear thereof, the lip O will fall behind the extensions into the slot I to fill the remainder of the said slot and thereby prevent the extension K from being moved. The moldboard A, land side C and share E being thus constructed, the operation of attaching the share to the plow is as follows: The extensions K are inserted in the vertical extensions of the slots I until the shanks of the extensions K strike against the upper horizontal wall of the lateral extensions of the slots I. When the extensions K on the moldboard side of the share are in this position, the extension K' on the land side of the share is opposite the slot F on the land side C. The share is now pushed rearward, forcing the extensions K along the horizontal extensions of the slots I and the extension K' into the slot F, until the said extensions reach the ends of the slots. The spring detent L is now turned until the lip O falls into the slot I behind one of the extensions K, to prevent the withdrawal of the said extension. By thus locking in position one of the extensions K, it will be observed that all of the extensions are held firmly in position in the slots in which they are seated. In this position the share is firmly secured on the plow. When now it is desired to remove the share from the plow, the spring detent L is raised by the hand hold N until the lip O is lifted out of the slot I, and the

detent is then swung to one side and released, to rest against the back of the plate B. The share is now free to be drawn forward, the extensions K traveling along the horizontal extensions of the slots I until opposite the vertical extension of the said slots I and until the extension K' is out of engagement with the slot E. The share is then drawn downward until the extensions K pass out of the slots I, whereupon the share is entirely removed from the plow.

It will be seen that the above-described operations are easily and quickly made. No tool has been used, nor has any bolt been unscrewed or screwed with the attendant risk of damaging screw threads or jamming of the same. With a plow thus constructed, it is possible to separate the share from the plow structure so quickly that the share can be more often removed and sharpened or replaced by sharpened shares, thus facilitating to a very large extent the operation of plowing.

Having thus described my invention, I claim as new and desire to secure by Letters Patent:

1. A plow comprising a moldboard, a

share to match said moldboard, means for locking the said share to said moldboard, embodying a sliding member, and a spring-retained key to hold the said sliding member in locked position.

2. A plow comprising a moldboard, a share to match said moldboard, means for locking the said share to said moldboard, embodying a sliding member, a plurality of open ended bayonet slots to receive and hold said sliding member, and a spring seated detent adapted to seat behind said sliding member to hold the same in said slots.

3. A plow comprising a moldboard having a series of open ended horizontal slots, a share to match said moldboard and having a series of projections adapted to be secured in the said slots by a sliding engagement, and a key to hold the said share in its secured position by closing one of said slots.

In testimony whereof I have signed my name to this specification in the presence of two subscribing witnesses.

HENRY H. JULICH.
